ERIC W. PALMQUIST, OF CHICAGO, ILLINOIS, ASSIGNOR TO AMERICAN STEEL
FOUNDRIES, OF CHICAGO, ILLINOIS, A CORPORATION OF NEW JERSEY.

BRAKE-HANGER MECHANISM.

1,325,531.

Specification of Letters Patent. Patented Dec. 23, 1919.

Application filed June 27, 1918. Serial No. 242,134.

To all whom it may concern:

Be it known that I, ERIC W. PALMQUIST, a citizen of the United States, residing at Chicago, in the county of Cook and State 5 of Illinois, have invented certain new and useful Improvements in Brake-Hanger Mechanism, of which the following is a specification.

This invention relates to brake hanger 10 mechanism.

The object of this invention is to provide a simple, inexpensive and durable brake hanger mechanism wherein a brake hanger may be readily applied, locked in operative 15 position, and readily removed from its co-operating support.

The invention is illustrated on the accompanying sheet of drawings, in which—

Figure 1 is a fragmentary side elevation 20 of a railway car truck embodying my invention;

Fig. 2 is a sectional view taken through the truck side frame and showing the hanger applied to the support; and,

Fig. 3 is a fragmentary plan view of the arrangement shown in Fig. 2 and showing the manner in which the hanger is applied to and withdrawn from its support.

The truck side frame 10 is provided with 25 a laterally extending bracket 11, to which a brake hanger 12 is connected, the lower end of the brake hanger being connected to a brake head 13 carrying a shoe 14 for co-operating with an associated truck wheel 15. The outer end of the bracket or support 11 is provided with a pair of jaws 16 and 17 having a receiving space 18 therebetween for the reception of the upper portion of the hanger 12, said jaws 16 and 17 and the space 35 18 being slightly inclined upwardly toward the associated wheel for the purpose of overcoming any tendency the upper end of the hanger may have in moving toward the wheel, it being appreciated, of course, that the weight of the beam, brake heads and 40 shoes is sufficient to hold the upper end of the hanger 12 in its lowermost position in the opening 18 between the jaws 16 and 17.

There are advantages in providing a continuous looped hanger, thereby overcoming the probability of a pin coming loose in the type of hanger which requires a pin for closing the ends of the hanger. Probably the most difficult problem in connection with 45 closed link hangers, such as shown in the

drawings, is the application of the hanger to its support and the withdrawal of the hanger therefrom, and at the same time retaining the hanger in its normal operating position when it is so placed.

To meet this problem I have provided the lower jaw 17 of the hanger bracket with a hooked projection 19 behind which one vertical leg of the hanger is placed when applying the hanger to its support. The 50 hanger is then given a movement about the vertical axis of one of the vertical legs, as shown in Fig. 3 of the drawings, the upper portion of the hanger passing into the receiving space 18. After the hanger is applied in this manner the lower end thereof is set in place in the brake head, it being understood that the brake shoe is removed when the hanger is applied to the head, the brake shoe thereafter being applied to the 55 head, causing the hanger to be locked to the head. With the hanger in the position shown in Figs. 1 and 2 of the drawings, it will be appreciated that the hanger cannot accidentally be withdrawn from its support, 60 it being impossible for the hanger to be given a vertical swinging movement, or a movement about one of its vertical legs as an axis, partly as a result of the hanger connection with the brake head. Under these 65 conditions it is impossible for the hanger to slide through the opening 18 between the jaws 16 and 17, and, as a matter of fact, the hanger is confined or locked in the position 70 shown in Figs. 1 and 2, thereby preventing 75 the hanger from being disconnected from its support and preventing the brake beam, head and shoe from falling to the track and occasioning serious results. The different 80 portions of the hanger may be any desirable size or shape, as desired.

It is my intention to cover all modifications of the arrangement shown in the figures of the drawings falling within the spirit and scope of the following claims.

I claim:

1. In brake mechanism, the combination of a support, and a brake hanger applied thereto in one position and moved into locking engagement with said support by a 85 swinging movement on a vertical leg as an axis.

2. In brake mechanism, the combination of a support, and a brake hanger applied thereto in one position and moved into lock- 90

ing engagement with said support by a swinging movement of one vertical leg about another vertical leg of said hanger as an axis.

- 5 3. In brake mechanism, the combination of a support having spaced jaws with an inclined opening therein, one of said jaws having a projection, and a hanger applied

to said support by placing a vertical leg of the hanger when in a vertical position behind said projection and swinging the upper part of said hanger into the opening between said jaws.

Signed at Chicago, Illinois, this 19th day of June, 1918.

ERIC W. PALMQUIST.
